UNITED STATES PATENT OFFICE.

JOHN MAYER, OF HAMILTON, ONTARIO, CANADA.

LINEMAN'S RING-PLIERS.

1,266,136.

Specification of Letters Patent. Patented May 14, 1918.

Application filed December 29, 1917. Serial No. 209,524.

To all whom it may concern:

Be it known that I, JOHN MAYER, of the city of Hamilton, in the county of Wentworth, in the Province of Ontario, Canada, have invented certain new and useful Improvements in Linemen's Ring-Pliers, of which the following is the specification.

My invention relates to improvements in linemen's ring pliers and the object of the invention is to devise a simple tool by which a lineman may easily, quickly and firmly clamp the rings to the messenger wire and at the same time provide simple means by which such rings may be easily, quickly and accurately spaced apart upon such wire prior to their being clamped in position and it consists essentially of the following arrangement and construction of parts as hereinafter more particularly explained.

Figure 1 is a general perspective view showing my tool in position ready for clamping a ring in place upon the messenger wire.

Fig. 2 is a similar view to Fig. 1, showing the tool in the clamping position with the ring clamped upon the messenger wire.

In the drawings like letters of reference indicate corresponding parts in the various figures.

1 indicates a messenger wire upon which the rings 2 are secured, such rings being provided for supporting the telephone cable. The rings 2 are split rings provided with upwardly extending hook-like portions 3 and 4 arranged in alinement so that the messenger wire 1 passes through these reversely set hook-like portions.

It has been found very difficult in practice to clamp these rings in position so that they will always be held firmly in place. In order to overcome this difficulty I have provided the following tool, the construction of which I will now describe.

5 and 6 indicate a pair of lever arms, the upper ends of which are curved inwardly at 7 and 8 and downwardly so as to overlap one another, the overlapping portions being reduced in thickness as at 7^x. 9 indicates a pivot bolt which extends through such overlapping portions in proximity to the lower end thereof, the portions through which such bolt extends being preferably thickened at 9^x. 10 and 11 indicate jaws

having semi-circular gripping portions 12 and 13, the jaws being widened out in opposite directions at 10^x and 11^x to the full width of the lever arms 5 and 6.

By this construction it will be seen that I have provided a tool which will have a great leverage and which, when brought into contact with the hook portions 3 and 4, will force them around the messenger wire so that they will grip it tightly in such a way that there will be no possibility of the ring slipping longitudinally of the wire.

14 indicates an orifice formed in one of the lever arms 5 or 6. 15 indicates a measuring wire, which extends at one end through such orifice 14 and is secured therein by a clamping screw 16. It will therefore, be seen that when one ring is clamped in position the free end of the wire 15 is placed against such ring, the position of the tool secured to the opposite end of the wire by the bolt 16 being so located as to gage the position in which the next ring should be located upon the messenger wire 1.

From this description it will be seen that I have devised a very simple form of tool by which the supporting rings may be easily, and quickly located and secured in position upon a messenger wire so that there will be no danger of their slipping from their position.

I am aware that other forms of pliers have been used before but no plier has yet been devised as far as applicant knows which will provide sufficient leverage to insure that the hook portions of the ring are clamped so tightly around the wire that no slip will occur. Furthermore no tool has yet been devised which will provide means for spacing the rings accurately an equal distance apart upon the messenger wire.

What I claim as my invention is:

A lineman's ring plier comprising two similar elements each substantially semi-cardioid in shape and having a handle at one end and a jaw at the other, a pivot securing the elements together between the handles and the jaws but being located above the jaws and the handles.

JOHN MAYER.
